DISENGAGEABLE CONNECTOR FOR A PRESSURE TESTER

Thure Ekman, Slalomvagen 12,
S-541 00, Skovde, Sweden

Filed Sept. 11, 1972, Ser. No. 287,911

Term of patent 14 years

Int. Cl. D10—07

U.S. Cl. D10—103

FIG. 2

FIG. 4

FIG. 1

FIG. 3

FIG. 1 is a side elevation of a disengageable connector for a pressure tester showing my new design;

FIG. 2 is a top plan view thereof;

FIG. 3 is a perspective view thereof; and

FIG. 4 is a bottom plan view thereof.

I claim:

The ornamental design for a disengageable connector for a pressure tester, as shown.
